UNITED STATES PATENT OFFICE.

EDGAR A. GILLINDER, OF TACONY, PENNSYLVANIA.

DESIGN FOR A LAMP-SHADE.

40,389.

Specification for Design.

Patented Dec. 7, 1909.

Application filed June 17, 1909. Serial No. 502,847. Term of patent 3½ years.

To all whom it may concern:

Be it known that I, EDGAR A. GILLINDER, a citizen of the United States, residing at Tacony, in the county of Philadelphia and State of Pennsylvania, have invented a new, original, and ornamental Design for Lamp-Shades, of which the following is a specification, reference being had to the accompanying drawings, forming part thereof.

2, is a side elevation, showing the design of the lamp shade.

I claim:

The ornamental design for a lamp shade, as shown.

EDGAR A. GILLINDER.
